DESIGN FOR AN APRON TONGUE SHOE

Henry W. Lambrecht, Baltimore, Md.

Application June 15, 1936, Serial No. 63,304

Term of patent 7 years

To all whom it may concern:

Be it known that I, Henry W. Lambrecht, a citizen of the United States, residing at Baltimore, in the State of Maryland, have invented a new, original, and ornamental Design for an Apron Tongue Shoe, of which the following is a specification, reference being had to the accompanying drawing, forming part thereof, in which:

I claim:

The ornamental design for an apron tongue shoe, substantially as shown.

HENRY W. LAMBRECHT.
